United States Patent Office.

THOMAS WALTER, OF PHILADELPHIA, PENNSYLVANIA.

Letters Patent No. 87,126, dated February 23, 1868.

IMPROVED SAFETY-GUARD FOR RAILWAY-CAR

The Schedule referred to in these Letters Patent and making part of the same.

To all whom it may concern:

Be it known that I, THOMAS WALTER, of the city and county of Philadelphia, in the State of Pennsylvania, have invented certain new and useful Improvements in Safety-Guards for Railroad-Cars, of which the following is a full, clear, and exact description.

The object of my invention is to prevent accidents to passengers in getting on or off, or to persons in any way liable to be run over by the cars; and

My invention consists in certain novel methods, hereinafter described, of combining, with a car, guards or fenders composed of rattan, or other equivalent elastic material, which will sweep any person falling upon the track, out of the way of the wheels.

In the accompanying drawings, which show the several modes in which I contemplate carrying out my invention—

Figure 1 represents a view, in perspective, of my improved safety-guard, adapted to a street-railway car, the red lines indicating the outlines of the car-body;

Figure 2 represents a view, in perspective, of the guard, as adapted to be applied directly to the bearings of the car, without a supporting-frame;

Figure 3 represents a transverse section, through the guard at the line x x of fig. 2, showing its mode of construction; and

Figure 4 represents a view, in perspective, of a guard with a hinge or joint, to allow vertical play.

In fig. 1, the red lines represent the lower portion of a car-body, mounted on trucks A, and provided with the usual springs and appliances of a completely-equipped car.

A frame is composed, in this instance, of two strips of metal, b b' , arranged parallel to each other on the outer and inner sides of the pillow-blocks B, which support the car.

These strips are held together by rivets b^2 , thus constituting a strong but light frame, for the attachment and support of the guard.

The guard consists of strips c , of rattan or bamboo, doubled over a central strip of wood, c' , and clamped between two wedge-shaped bars c^2 c^3 , by screws c^4 , (see fig. 3.) By this means I form a simple, cheap, and effective guard, and can vary the angle of inclination of the guard, by varying the angle of the wedge-bars c^2 c^3 .

In fig. 1, the front guard D is shown as constructed of two strips, rigidly united at their inner ends, so as to form a plow-shaped guard, with its outer ends projecting beyond the tracks.

This guard is suspended by hooks d from the frame b b' , above described.

The rear guard D', fig. 1, is constructed so as to embrace three sides of the car in a rigid frame, as will be obvious from the drawing.

The frame and guard above described can easily be adapted to cars now built. It is obvious, however, that the entire car might be enclosed in a rigid guard-frame. The frame b b' , it will be observed, rests loosely on the bearings B', and thus maintains its proper relation to

the rails, irrespective of the vertical oscillations of the car on its springs.

In fig. 2, I have shown a method of suspending the guard directly from the bearings B', by straps e , which arrangement dispenses with the frame b b' .

In order to hold the guard firmly in its normal position, and yet allow it to yield, in case the car gets off the track, and thus prevent the breaking of the guard, I suspend the guard from the car by a hinged strap, F, provided with a rigid stop, f, which prevents the guard from yielding inwardly, and with a spring-stop, f', to prevent it yielding too far outwardly.

In fig. 4, I have shown the guard as provided with a hinge, G, which allows either section to play vertically without the other.

Metal rods might be used, but would not answer so good a purpose, besides being more expensive.

By my improvement, accidents to passengers, by falling or slipping under the cars in getting on or off, (which accidents are at present of such frequent occurrence,) will effectually be prevented, and any persons falling or thrown on the track, will be removed, without being run over by the wheels or crippled by the guard.

I am aware that cow-catchers have long been used to sweep obstacles from a railroad-track, and that brooms also have been used to sweep the rails. I am also aware that rigid fenders have been used to prevent passengers getting under the wheels; but I am not aware of the previous use of a guard or fender composed of independent elastic rods, which run in contact with or very near the rails, yield inwardly to the inequalities of the road, and are yet rigid enough to throw obstacles out of the way of the wheels.

What I claim as my invention, and desire to secure by Letters Patent, is—

1. The framing b b' , for the guard, constructed as shown in fig. 1.

2. The petticoat or rigid frame-guard D', constructed and applied as shown in fig. 1.

3. The combination, substantially as set forth, of a broom-supporting frame, resting on the axle-boxes or bearings of the car, and a fender or guard suspended from the frame, for the purposes specified.

4. Attaching the broom directly to the axle-boxes, as shown in fig. 2.

5. The combination, substantially as set forth, of a safety-guard, with a car, by a hinge, a stop to prevent inward deflection, and a spring to resist outward pressure, as specified.

6. A safety-guard, composed of strips of rattan or bamboo, compressed between angular blocks, as set forth, to give the desired inclination to the fender, and facilitate repairs.

In testimony whereof, I have hereunto subscribed my name.

Witnesses: THOMAS WALTER.
